CLAIM

The ornamental design for a disposal stopper-strainer-brush, as shown and described.

DESCRIPTION

FIG. 1 is a perspective view of the disposal stopper-strainer-brush showing our new design;

FIG. 2 is a bottom plan view thereof;

FIG. 3 is a top plan view thereof;

FIG. 4 is a front elevational view thereof, the opposite rear being a mirror image thereof; and,

FIG. 5 is a right side elevational view thereof, the left side being a mirror image thereof.
